UNITED STATES PATENT OFFICE.

WILLIAM D. BROWN, OF SOMERSET, KENTUCKY.

SHOCK-ABSORBER.

1,346,739.

Specification of Letters Patent. Patented July 13, 1920.

Application filed September 20, 1919. Serial No. 325,057.

To all whom it may concern:

Be it known that I, WILLIAM D. BROWN, a citizen of the United States, residing at Somerset, in the county of Pulaski, and 5 State of Kentucky, have invented new and useful Improvements in Shock-Absorbers, of which the following is a specification.

This invention comprehends the provision of a shock absorber and particularly designed for use in connection with Ford automobiles, the invention being in the nature of an attachment so that it can be applied to the car without any change or alteration in the construction of the latter.

15 In carrying out this invention, use is made of an arm arranged above the usual body supporting spring, the arm being pivotally associated at one end with the usual clevis which supports the end of the spring, while 20 the opposite end of the arm is connected with the frame of the car by means of a resilient element designed to absorb the shock or jars incident to the travel of the car over irregular surfaces.

25 The nature and advantages of the invention will be better understood when the following detail description is taken in connection with the accompanying drawing, the invention residing in the construction, combination and arrangement of parts as 30 claimed.

35 In the drawing forming part of this specification, like numerals of reference indicate similar parts in the several views and where-
in :—

Figure 1 is a fragmentary elevation of a portion of the car showing the shock absorber applied thereto.

40 Fig. 2 is a sectional view taken on line 2—2 of Fig. 1.

Fig. 3 is a perspective view of the attachment removed from the car.

Fig. 4 is a similar view of the spring and its attaching plate therefor.

45 Referring to the drawing in detail 10 indicates the brake drum housing, 11 the usual body supporting spring, which is terminally supported by means of the clevis 12 including the fixed portion 13 which is secured to 50 said housing.

55 The attachment forming the subject matter of my invention consists of an arm 15 having one end flattened as at 16, while the opposite end is bifurcated as at 20. The arm is also provided with a transverse bore 18 disposed adjacent the bifurcated extrem-

ity, and the purpose of this bore will be hereinafter described. A plate 19 supports the spring, the latter being formed with an intermediate loop 20 which reposes upon the 60 plate 19, the opposite edges of the plate being ruled to embrace the respective limbs of the loop as clearly shown. The respective limbs of the loop terminate to provide coils 21, while the outermost convolution 22 65 of each coil terminates to provide a hook 23. The plate 19 in the association of parts is positioned beneath the flat broad extremity 16 of the arm, and these parts are secured together by means of a fastening bolt 70 24 which is passed through said parts and has associated therewith a nut 25. The hooks 23 of the spring are received within eyes 26 of a substantially U-shaped supporting member 27.

75 In applying the shock absorber, the clevis 12 is separated from its fixed member 13, these parts having originally been associated for the purpose of supporting the end of the spring 11 in the usual well known manner. 80 The arm 15 is positioned upon the spring 11, and the separated portions 29 defined by the bifurcated extremity are brought into alignment with the bore in the fixed member 13. The bolt 30 is passed through the parts to 85 provide a pivotal connection between the same, the bolt of course being equipped with nuts for holding the parts operatively associated. The fastening element herein indicated at 32 which was primarily employed 90 for holding the clevis 12 and the fixed member 13 associated, is now passed through the clevis and the bore 18 of the arm, and in this manner the terminal of the spring 11 is properly supported from the arm. The 95 U-shaped member 27 straddles the frame A and supports the spring. With the parts thus arranged proper pivotal movement between the opposite ends of the arms and their associated parts is provided for, while 100 the spring yieldably supports the adjacent extremity of the arm and consequently absorbs a great deal of the vibration to which the car is subjected, when going over irregular surfaces. The invention is very merito- 105 rious, can be manufactured and sold at a nominal cost and can also be applied to any Ford car without making alterations.

110 While I have shown and described what I consider the preferred embodiment of the invention, I desire to have it understood that I do not limit myself to these exact de-

tails, as such changes may be resorted to when desired as fall within the scope of what is claimed.

What I claim is:

- 5 1. The combination with a vehicle, having a bracket secured to the axle housing, and a shackle carried by the terminal of the body supporting spring, of an arm having one end pivotally connected with said bracket, a
- 10 coiled spring formed to provide an intermediate loop projecting at an angle from the convolutions of said spring, means for securing the loop to the opposite end of said arm, means for suspending said coiled spring from the chassis of the vehicle, and means for securing said shackle to the arm at a point intermediate its ends.
- 15 2. The combination with a vehicle having a bracket secured to the axle housing, and a shackle carried by the terminal of the body supporting spring, of an arm arranged above the spring in parallelism therewith, one end of the arm being pivotally associated with said bracket, the opposite end of
- 20 the arm being flat, a coiled spring formed
- 25

to provide a horizontally disposed intermediate loop, means for associating said loop with the flat end of the arm, means for securing the coiled spring to the chassis of the vehicle, and means for securing said shackle to the arm at a point intermediate its ends.

3. The combination with a vehicle having a bracket secured to the axle housing and a shackle carried by the terminal of the body supporting spring, of an arm arranged above the spring in parallelism therewith, said arm being pivoted at one end to said bracket, a coil spring formed to provide an intermediate loop projecting at an angle from the convolutions of said coil, means for associating the loop with the opposite end of the arm, a yoke embracing the chassis of the vehicle, and associated with the spring holding the parts together in operative relation, and means for securing said shackle to the arm at a point intermediate its ends.

In testimony whereof I affix my signature.

WILLIAM D. BROWN.
